United States Patent Office

Des. 224,166

Patented July 4, 1972

224,166

MICROFICHE VIEWER

Lewis E. Simpson, Inglewood, Calif., assignor to
Dioptrix, Inc., La Jolla, Calif.

Filed Apr. 6, 1971, Ser. No. 131,853

Term of patent 14 years

Int. Cl. D16—02

U.S. Cl. D61—1

FIG.1

FIG.2

FIG.3

FIG.4

FIG.5

FIG. 1 is a perspective view of a microfiche viewer showing my new design;

FIG. 2 is an end view, in enlarged scale, of the microfiche viewer shown in FIG. 1;

FIG. 3 is a front view, in enlarged scale of the microfiche viewer shown in FIG. 1;

FIG. 4 is a rear view, in enlarged scale, of the microfiche viewer shown in FIG. 1;

FIG. 5 is a top plan view, in enlarged scale, of the microfiche viewer shown in FIG. 1.

I claim:

The ornamental design for a microfiche viewer, substantially as shown.
